UNITED STATES PATENT OFFICE.

BURNSIDE E. SAWYER, OF ATHOL, MASSACHUSETTS.

DESIGN FOR A COMBINATION-SQUARE.

SPECIFICATION forming part of Design No. 29,875, dated December 27, 1898.

Application filed November 30, 1898. Serial No. 697,919. Term of patent 14 years.

To all whom it may concern:

Be it known that I, BURNSIDE E. SAWYER, a citizen of the United States, residing at Athol, county of Worcester, and State of Massachusetts, have invented and produced a new and original Design for a Combination-Square, of which the following is a specification, reference being had to the accompanying drawings, forming part hereof, in which—

10 Figure 1 is a side view of a combination-square, showing my design. Fig. 2 is an end view of the same. Fig. 3 is a section on the irregular line 3 3 of Fig. 1.

The leading feature of my design consists

in the form of the web of the square, the same 15 having a practically circular central opening *a*, the edge *b* of the web around said opening being raised or beaded, as shown. The curvilinear edge *c* of the web is also similarly provided with a head, as shown.

What I claim is—

The design for a combination-square, as shown and described.

BURNSIDE E. SAWYER.
